EXPANSION ENGINE

John Merritt Clark, Northfield, N. J.

Application August 24, 1938, Serial No. 226,421

4 Claims. (Cl. 121—163)

This invention relates to expansion engines, especially to engines having a fluid-pressure cylinder with a piston working therein and admission and exhaust ports through which the entrance and exhaust of the expansible fluid is controlled by a valve.

In such engines, as usually constructed, the closure of the exhaust port commences while the piston is still a considerable distance from the end of its stroke resulting in a back pressure being formed against the piston which reduces the power of the engine and considerably decreases its efficiency. Also the valve in such engines uncovers the admission port gradually so that a substantial time interval results between the time of opening the admission port and the time when the full fluid pressure is applied to the piston to advance it along the cylinder.

It is an object of my invention to increase the efficiency and power of such engines by relieving the back pressure acting against the piston by causing the exhaust port to remain open until the piston has more nearly completed its stroke, thereby providing a passage of large area for the spent fluid. In accordance with my invention this object is secured by a novel form of valve gear operating to effect closure of the exhaust port while the piston is advancing only a short distance near the end of its stroke.

In accordance with a further object of the invention, a novel type of valve gear is provided in which a valve moves rapidly across the admission port while the piston is near the end of the cylinder so as to provide a large area for the admission of steam or other expansible fluid in order to quickly build up the full available fluid pressure behind the piston.

In pursuance of a further object of the invention, I provide in association with such a valve gear means which may include a novel eccentric arrangement which is connected to the valve rod and which serves to delay the time of commencement of closure of the exhaust port. By a further provision of the invention, the same eccentric arrangement is designed to move the valve rapidly across the admission port while the piston is near the end of the cylinder, thereby providing the full pressure of the fluid for advancement of the piston.

Other objects and advantages will appear as the description of the particular physical embodiments selected to illustrate the invention progresses. For a better understanding of the invention, however, reference is made to the ac-

companying drawings in which like reference characters designate like parts throughout the several views, and in which:

Fig. 1 is a fragmentary view in elevation of an embodiment of the invention as applied to a locomotive drive with the piston in substantially its mid-position and with portions of the cylinder and valve chest shown in section;

Fig. 2 is a view similar to Fig. 1 showing the parts in position just before closure of an exhaust port and with certain levers and links represented diagrammatically;

Fig. 3 is a view similar to Fig. 2 showing the positions of the parts when the piston is at the end of a stroke;

Fig. 4 is a view similar to Fig. 2 showing the positions of the parts just before the travel of the valve is reversed;

Fig. 5 is a view similar to Fig. 2 but with the parts in position just before the closure of exhaust port when the piston is near the forward end of the cylinder;

Fig. 6 is a vertical sectional view at line 6—6 of Fig. 1 showing the guideway, slide and a portion of the slide operating mechanism;

Fig. 7 is a top plan view of one of the valve operating slides shown in Fig. 1;

Fig. 8 is a view showing the relative positions of the piston and valve if the valve rod and slide were integral and with no relative motion between them;

Fig. 9 is a view showing a modified form of the invention and, Fig. 10 is a view of a further modified form of the invention.

Referring to Fig. 1, the invention is shown as applied to a steam locomotive having a main drive wheel 10 having a crank pin 11 which is connected to crosshead 12 by a main driving rod 13, the crosshead being slidable in a guideway 14 formed between the parallel guide rods 15 and 16 and being connected to a piston 17 by a piston rod 18. A crank arm 19 is secured to crank pin 11, the end of which is pivotally connected, as by a pin 20 to one end of a rod 21 whose other end is pivotally connected to a main reverse link 22. A support pin 23 which is carried by a stationary frame member 24 serves as a pivotal support for reverse link 22. A radius rod 25 carries a block 26 which is slideable in a slot 27 formed in reverse link 22, the position of the block 26 being controlled by the engineer from the cab (not shown) of the locomotive through a link 28, bell crank lever 29 having arms 30 and 31, and link 32 whose lower end is pivotally connected to the end of radius rod 25, as by a pin 33.

33. As shown, the bell crank 29 is pivotally supported by a pin 34 carried by a bracket 35 secured to frame 24.

The front end of link 25 is pivotally connected by a pin 36 to the upper end of a floating lever 37 whose lower end is connected to crosshead 12 by a link 38. A pin 39 on lever 37 has pivotally connected to it a slide 40 slidable in guideways 41 formed in the spaced parallel guide rods 42 and 43 (Fig. 6). A valve 44, preferably of the type having spaced apart cylindrical ends formed as pistons 45 and 46, is mounted for reciprocation within a steam chest 47 to which steam under high pressure is supplied by a pipe 48 through a main admission passage 49. Valve 44 is operated from slide 40 through a valve rod 50 whose end is secured to a slide 51 which is in turn pivotally connected by a pin 52 to an eccentric strap 53 encircling an eccentric 54. Eccentric 54 is preferably formed integral with a lever 55 which is pivotally supported on a pin 58 secured to the parallel depending extensions 59 formed on slide 40, (Fig. 6). As shown more clearly in Fig. 7 the slide 40 is preferably formed of two spaced parallel side members 60 and 61 which are integrally connected by a transverse portion 62.

In order to provide an additional control over the valve 44 in addition to its control by the slide 40, I provide means for oscillating eccentric 54 about its pivotal support 58 thereby causing the valve 44 to approach or recede from slide 40. This additional control means comprises a link 63 whose forward end has spaced apart ears 64 between which the upper end of lever 55 is pivotally supported as by a bolt 65 having a retaining nut 66 (Fig. 6). The rear end of link 63 is pivotally connected by a pin 67 to the upper end of a floating lever 68 whose lower end is pivotally supported on a pin 69 secured to a slide 70 reciprocable in a guideway 71 formed in a guide member 72. A link 73 connects pin 69 to an intermediate point 74 on a rock lever 75 pivotally supported on a stud 76 the lower end of rock lever 75 being in turn connected to floating lever 37 by a link 76a as shown (Fig. 1). Floating lever 68 is also connected to slide 40 by a short link 77 one end of which is pivotally mounted on pin 39 and its other end pivotally connected to lever 68 by a pin 78.

Steam is admitted to and exhausted from cylinder 79 through the admission and exhaust ports 80 and 81 and a series of orifices 82 formed in the valve seat liners 83. Main exhaust passages 84 and 85 are provided near the ends of steam chest 47 through which the spent steam is exhausted under the control of valve 44.

It will be readily understood from the foregoing disclosure that when the parts are in the relative positions illustrated in Fig. 1, steam will be admitted to the front end 86 of cylinder 79, the main steam supply entering the chest 47 from supply pipe 48 through passage 49 and leaving the chest through the orifices 82 which are at all times in communication with port 80, through which the live steam enters the front end of the cylinder. Valve 44 is shown disposed with its front piston 45 in position to block exhaust to the exhaust passage 84 while its piston 46 is disposed so as to leave the exhaust passage 85 wide open for spent steam from the rear end 87 of the cylinder, which passes through exhaust port 81 and orifices 82. It will also be noted that eccentric 54 has been advanced to a position at the left of its pivotal mounting pin 58 so

as to position valve 44 farther to the left than it would otherwise be, thereby delaying the time of closure of exhaust port 81 by piston 46, the expansion of the steam in the cylinder 79 being subsequently effective to move the piston 17 to the end of its stroke. As the steam pressure advances the piston 17 into the position shown in Fig. 2, the link 63 and its associated parts retains lever 55 and eccentric 54 in position at the left of pivot pin 58, in order to delay closure of the exhaust port 81 until piston 17 is near the end of its stroke. This delay in closure of the exhaust port reduces very considerably the back pressure built up in the rear end 87 of the cylinder and therefore increases the mean effective pressure applied to the piston during the stroke. Also, as shown in Fig. 2, the piston 45 has closed the port 80 and thereby shut off the supply of live steam to the latter and front end 10 of the cylinder. As the slide 40 is being moved to the right from the position of Fig. 2 into that of Fig. 3, link 63 and its associated parts rock lever 55 and eccentric 54 towards the right about pivot pin 58 so as to advance valve 44 over a greater distance than that travelled over by slide 40. This action results in a rapid motion of valve 44 so that the exhaust port 80 is put into full communication with exhaust passage 84 by piston 45 to permit free exhaust of the steam in the front end 86 of the cylinder. Piston 46, as shown in Fig. 3, has been moved into position to prevent the passage of spent steam into exhaust passage 85 and to uncover orifices 82 to admit live steam into port 81.

As the parts move from the position of Fig. 3 into that of Fig. 4 reverse link 22 causes radius rod 25 to move lever 55 and eccentric 54 quickly to the right about pivot pin 58, through the links 63, 77 and floating lever 68. This rapid motion causes piston 46 to fully open port 81 to the admission of live steam from chest 47 so that a high steam pressure is quickly built up behind piston 17 in the rear end 87 of the cylinder, thereby increasing the power developed during each piston stroke. It will also be observed from an inspection of Fig. 4 that with the eccentric 54 positioned to the right of its pivotal support 58, piston 45 fully uncovers the orifice 82 so as to provide a free passage for spent steam through exhaust port 80 and exhaust outlet 84. This free passage for the exhaust is maintained until just before the parts reach the position shown in Fig. 5, while live steam is entering the rear end 87 of the cylinder. In the position shown in Fig. 5, the valve gear shown is moving slide 40 to the left and also rotating eccentric 54 to the left about its pivotal support 58 so that exhaust port 80 will be soon opened by piston 45 for the admission of live steam and port 81 soon opened by piston 46 for the passage of exhaust steam from rear end 87 of the cylinder.

Referring to Figs. 8 and 2, the valve 44 is in the same position in each and Fig. 8 shows the corresponding position piston 17 would have if valve rod 50 and slide 40 were made integral and hence with no relative motion between them. The gain in the period of exhaust and in the expansion of the live steam by use of my invention is represented by the difference in the positions of the piston 17 as shown in these two figures.

In the modified form of the invention shown in Fig. 9 and in which like numbered parts correspond to those shown in Fig. 1, the eccentric 56 is replaced by a floating lever 88 mounted on 75

5 pivot pin 82 carried by slide 40, the upper end of lever 88 being connected to valve rod 50 by a short link 90 and the lever being rocked on its pivotal support 82 by the link 73 and rock lever 75. In this modification, the slide 70 and its 10 associated parts are not used but the same beneficial results are secured as in the form of my invention shown in Fig. 1, the oscillation of lever 88 serving to delay the time of closure of the exhaust ports 80, 81 and thereby achieve the 15 object of the invention by providing a free passage of large area for the spent steam or other fluid.

10 The modification shown in Fig. 10 is in all respects similar to that shown in Fig. 9 except that the leverage of lever 88 is made adjustable. As shown, three holes 82b are arranged one above the other in the slide 40a and in lever 88a and the fulcrum pin 82a may be fitted in either of the 20 registering holes to thereby provide a control means for increasing or decreasing the extent of travel of valve 44. It will thus be apparent that by the provision of this adjustable fulcrum on slide 40a, the amount of retarding 25 action given to the valve to delay the closing of the exhaust ports 80 and 81 may be controlled to any desired extent.

30 In both forms of the invention shown, the reverse link 22 operates in the usual manner to cause an earlier cut-off of steam to the admission ports 80, 81 as the block 26 is adjusted toward the pivotal support 23 of the link and to cause a reversal in the direction of rotation of the engine when it is moved into a position on the opposite 35 side of support 23 from that shown in Figs. 1 and 9.

35 I have described what I believe to be the best embodiments of my invention. I do not wish, however, to be confined to the embodiments shown, but what I desire to cover by Letters 40 Patent is set forth in the appended claims.

I claim:

1. In an engine having a valve adapted to open and close steam ports therein and a reciprocating piston, a valve gear for maintaining the mean effective pressure at a high value throughout the stroke by lengthening the time of motion of the valve at any cut-off point and comprising a substantially straight guideway, a slidable member mounted for reciprocation in said guideway and means connecting the valve and slidable member and adapted to vary the distance therebetween, 5 said connecting means comprising a lever pivoted to the slidable member at a point intermediate the ends thereof, and a link having one of its ends connected to one end of the lever and its other end to the valve. 10

15 2. A valve gear as set forth in claim 1 in which the lever is provided with a plurality of apertures spaced apart in the direction of its length to provide selective pivotal points of support on the slidable member. 20

3. A valve gear as set forth in claim 1 in which said lever is disposed in a substantially vertical position when the engine piston is at the end of its stroke. 25

4. In an engine having a valve adapted to open and close steam ports therein and a reciprocating piston, a valve gear for maintaining the mean effective pressure at a high value throughout the stroke by lengthening the time of motion of the valve at any cut-off point and comprising a substantially straight guideway, a slidable member mounted for reciprocation in said guideway, means connecting the valve and slidable member for varying the distance therebetween and comprising a lever pivoted to the slidable member, 30 and means for oscillating said lever comprising a rock lever, a pivotal support for the rock lever disposed at a level above the piston and a link connecting the lever and an intermediate point of the rock lever. 35

JOHN MERRITT CLARK. 40
